HAT FLANGING IRON

Paul Schultze, Danbury, Conn., assignor to Doran Bros., Inc., Danbury, Conn., a corporation of Connecticut

Application October 1, 1937, Serial No. 166,759

13 Claims. (Cl. 223—21)

This invention belongs to the class of hat brim flanging or ironing machines and refers more particularly to an improved form of iron employed to travel over the surface of the hat brim for the purpose of smoothing and shaping the same.

The invention particularly applies to the member, in this type of flanging machine, known as an iron and comprises not only a novel construction of iron for operating on the hat brim, but also an associated means for heating the iron as well as to provide a warm stream of air on the surface of the hat, being operated upon and whereby the latter becomes somewhat dried out during the operation of ironing and shaping the brim to the block upon which it is mounted, and whereby the shape and style of the hat brim is determined.

The invention is particularly adaptable and, in fact, has been applied to the type of hat brim flanging machine shown and described in my pending patent application filed December 3, 1936, Ser. No. 117,310. This prior application has to do more particularly with the general construction of the machine and as shown employs a commercial type of iron for ironing the hat brim. In this machine the iron is supported upon an automatically controlled operating arm that serves to guide the iron across the under brim portion of the hat and to automatically disengage it from the hat at the completion of an operation.

I have, therefore, illustrated my present invention, as applied to the automatically controlled operating arm as illustrated in the said prior application, and in this connection will necessarily refer to and describe so much of the machine and its iron carrying arm as may be necessary to convey a clear understanding of the application of the present invention.

The iron of the present application is formed in part of a pair of co-acting plates hingedly supported and connected so as to conform to the rolled surface of the under side of a hat brim during the flanging operation, better to prevent any possible marking of the surface of the brim as may occur with a one piece iron.

The electrical heating means forming a part of this invention, as shown in the drawings, is closely associated with the iron and serves to heat the volume of air that is fed through the heating element and thence against and past the ironing members and finally disposed against the surface of the hat. The heating element is provided with automatic means for controlling the electric cur-

rent so that the proper air temperature may be provided.

The invention accordingly consists in the features of construction hereinafter set forth including combinations of elements and arrangements of parts as will be described in the following specification and shown in the accompanying drawings forming a part of this specification and as will be more particularly indicated in the claims to follow.

In the accompanying drawings is shown a practical embodiment of my present invention such as is adapted for use in various types of hat flanging machines.

Fig. 1 shows a top plan view of my improved flanging iron including its heating element and the arm for supporting the iron, said iron being in position for the beginning of a flanging operation on the underbrim portion of a hat.

Fig. 2 shows a detached side elevation of my improved iron, together with its heating element, and a portion of the supporting arm shown in Fig. 1.

Fig. 3 shows a bottom plan view of the iron shown in Figs. 1 and 2.

Fig. 4 shows a central vertical longitudinal sectional view taken on line 4—4 of Fig. 1, better to illustrate the internal construction of the iron including the heating element and associated features of a flanging machine and its iron supporting arm.

Fig. 5 shows a sectional elevation, as seen from the right of Fig. 4, of a part of a hat supporting block, a hat, a cloth covering the same and my improved iron, in a starting position, for operating on the under brim portion of a hat when mounted upon the block.

Fig. 6 shows a somewhat similar view, though illustrating the iron in an advanced position, operating upon the under-curved portion of the brim, and

Fig. 7 shows another somewhat similar view illustrating a portion of the lathe, hat block, hat and cloth covering the latter, together with the iron in its finishing position, preparatory to being thrown off from the hat.

In flanging machines of the present type wherein the hat body and the ironing element are designed to move with respect to each other, a lathe is usually employed, upon which to mount the hat block and hat as will be seen from my design of machine shown in the aforesaid pending application and in fact other commercially known flanging machines. While I have not deemed it necessary for the disclosure of my

iron, in this application to illustrate a complete lathe, yet in order to convey a clear understanding of the purposes and advantages of my improved iron, I have shown a part of a lathe structure, in Figs. 5, 6 and 7, which I have designated as 19, the same being a holder which, in practice, is formed of metal and may be supported directly upon the lathe spindle, not shown. This holder is provided with one or more screws 20 having vertically projected pin-like ends that project above the annular flat top surface of the holder upon which a hat block 21 is positioned, the hat block being provided with holes 22 to receive the pins and whereby the block is properly supported and its rotary movement with the holder and lathe spindle is assured.

In the drawings, 23 indicates the hat body which is shown in an inverted position in Fig. 1, the smoothing iron 18 being positioned upon the under side of the brim preparatory to its movement, in the direction of arrow, across the oval under surface of the brim. In Figs. 5, 6 and 7 where a cross section of a portion of the hat body is shown, 24 obviously represents the inner band 25 portion of the hat body whereas 25 indicates the curled brim portion lying close to the curling surface of the block to which the brim of the hat is made to conform. In practice, for the purpose of a flanging operation the under surface of a hat body is covered with a wet cloth, herein designated as 26, which is snugly stretched over the hat and secured to the block by means of a cord which in the drawings is designated as 27 which insures the holding of the hat brim down upon the block during the flanging operation and allows the quick removal of the cloth when the brim has been flanged. From this disclosure, it will be obviously apparent that the heated smoothing plates of the iron engage the damp cloth, and not the hat brim proper, thereby performing an operation similar to that used by tailors and others in the pressing of garments.

Referring again to the arm 16, see Figs. 1, 2 and 4, it will be seen that it is in part bifurcated 45 having intervening bridge members 28 that form the supports for the switch mechanisms 29 as well as the air heater 30, mounted above the switch. The ironing element 18, which includes a pair of hingedly mounted steel plates 31 and 50 32, is carried by the arm 16 through the medium of a hollow shaft 33 rockably mounted in the before-mentioned bridges 28 of the arm 16.

The iron 18, as will be seen, is made up of an inner shell 34 having an air intake passage 35 55 leading into an enlarged portion 36, that houses the ironing plates 31 and 32 and which are hingedly mounted on shafts 37 secured in the lower part of the inner shell 34. One end portion of these plates are provided with segments 38 60 that engage each other to insure rocking of the one, with the rocking movement of the other, thereby causing the two plates to rock in unison with each other, better to conform to the surfaces of the hat brim, while the iron is being moved over the hat brim in its flanging operation.

The plate 31 of the iron, as will be seen from Figs. 3, 5, 6 and 7, is slightly wider than the associated member 32 so that the said wide plate can better perform a finishing flanging movement 70 across the under flat face of the brim, see Fig. 5.

The upper portion 39 of the passage 35 where it receives the end portion of the short pipe 40 secured in the heating unit is relatively wide so as to permit of a rocking movement of the iron 75 together with the hollow rockable shaft 33 upon

which it is mounted and it at the same time forms a stop to limit the rocking movement of the iron with respect to the arm 16 and its attached heating unit.

The heating unit 30, see Fig. 4, comprises an inner tube 41 with which the beforementioned short pipe 40 is connected. This tube 41 is lined with insulating material 42 in which the coil of resistance wire 43 is supported. One end of the coil, as will be seen, is connected with a binding post 44 while the other end is similarly connected to the post 45, said post being mounted in the outer cylindrical casing 46, and the intermediate shell 47, thus providing means for supplying electric current from any suitable source. The heating element is preferably in the form of a coil 43 which snugly fits into the insulative lining 42 of the tube and forms an elongated passage through which the air passes to be heated on its travel to the ironing plates, see arrows. This heating element and its insulation are contained within the tube 41 supported within and in spaced relation to the shell 47 which latter is likewise contained within and in spaced relation to the casing 46. The inner end of the tube 41 is provided with an opening 48 through which the air enters the heating chamber and the opposite end of the intermediate shell 47 is also open, forming an air passage, see arrows, from the supply pipe 49 as between the members 46 and 47 thence between the members 47 and 41 through the opening 48 to the heating chamber from whence it passes through the short pipe 40 into the passage of the iron. This construction obviously forms preliminary heating passages through which the air is conducted to the heating unit preparatory to its being heated and forced on through the heated iron in a way to heat the plates and dry off the surface of the hat as the iron is carried across it. The air supply pipe 49 may obviously be connected to any suitable source of air supply as for instance a fan, not shown, which in practice would be mounted upon and form a part of the flanging machine on which the iron is used.

The iron which has been generally designated as 18 is made up of three principal metal parts, an inner member 34, in which the passages 35 and 36 are formed and the two outer metal covering shells 50 and 51. The space between these two shells, see Fig. 4, is filled with suitable insulating material 52 to retain the heat of the air passing through the iron and likewise leaving the outer surface of the iron relatively cool, better to permit of handling the same as occasion may require. These outer shells as will be seen are secured in position in a way to closely contact the insulation against the inner shell member and are secured together in position by screws 53.

As before stated, I have provided an automatic temperature control within the iron with connection with the switch 29 for cutting in and out the electric current to the heat element, which will best be understood from Fig. 4 of the drawings. This, as will be noted, is contained, in part, within the before-mentioned hollow rockable shaft 33 that extends into and supports the iron. A push rod 54 is slidably mounted in this hollow shaft, with its front end projecting slightly within the iron in the path of movement of a diaphragm 55 mounted within the head and adapted to be flexed by the temperature within the iron in a manner to engage and disengage said contacting rod with the raising and lower-

ing of the temperature within the iron. The other end of the tube is in alignment to engage a contacting member of a switch 56 whereby the electric current provided for the heating element and through the aforementioned binding posts are controlled. The current obviously may be provided from any convenient source and connected with the iron as may be required.

Having thus described my invention, what I claim and desire to secure by Letters Patent is:

1. In an iron for hat flanging machines, the combination with an arm for supporting an iron, of a rockable support carried thereby, an iron carried on said rockable support and having an air duct passing therethrough, ironing plates mounted in the mouth of the air duct, an electric heating unit carried on the arm and connected with the air duct, and an air supply pipe connected with the heating unit for passing air thereto and through the iron.

2. In an iron for hat flanging machines, the combination with an operable arm for supporting an iron, of a rockable support carried thereby, an iron carried on said rockable support and having an air duct passing through the iron, hingedly connected ironing plates pivotally mounted in the mouth of the air duct, an electric heating unit carried by the ironing arm and connected with the air duct, an air supply pipe connected with the heating unit for passing air thereto and through the duct of the iron and in a manner to heat the plates.

3. In an iron for hat flanging machines, the combination with an operable arm for supporting an iron, of a rockable support carried thereby, an iron carried on said rockable support and having an air duct extending through the iron, ironing plates mounted in the mouth of the air duct, an electric heating unit carried by the ironing arm and connected with the air duct, an air supply pipe connected with the heating unit for passing air thereto and through the iron, hingedly connected ironing plates pivotally mounted in the mouth of the air duct, and temperature control means within the air duct for regulating the temperature of the heated air.

4. In an iron for hat flanging machines, the combination with an operable arm for supporting an iron, of a rockable support carried thereby, an iron secured on said rockable support having an air duct passing therethrough, ironing plates pivotally mounted in the mouth of the air duct, an electric heating unit carried by the ironing arm and connected with the air duct, an air supply pipe connected with the heating unit for passing air thereto and through the iron, the said iron comprising an inner shell in which the warm air duct is formed, an outer shell and a filling of insulating material between the two shells.

5. In an iron for flanging machines, the combination with an operable arm for supporting an iron, of a rockable support carried thereby, an iron secured on said rockable support having an air duct passing therethrough, an ironing plate mounted in the mouth of the air duct, an electric heating unit carried by the ironing arm having an air duct connected with the duct of the iron, the said heating element being fixedly supported with respect to the rockable ironing arm.

6. In an iron for flanging machines, the combination with an operable arm for supporting an iron, of a rockable support carried thereby, an iron secured on said rockable support, an air duct passing through the iron, ironing plates mounted in the mouth of the air duct, an electric heating unit carried by the ironing arm and connected

with the air duct, the said heating element including a series of elongated tubular sections, one within the other, and including an outer air intake, an intermediate air warming passage, an inner section and a heating unit within the inner section, and an outlet from the heating unit leading to the hot air passage in the iron.

7. In a hat flanging machine of the class described, the combination with a vertically rotatable lathe for supporting a hat block, of a hingedly supported arm, an iron carried by said arm, means for operating the arm to move the iron radially with respect to the axis of the lathe, the said iron including an air passage therethrough, a heating element associated therewith to warm the current of air through the iron, an ironing plate pivotally mounted in the mouth of the warm air passage to engage and operate upon the surface of a hat.

8. In an iron of the class described, the combination of an operating arm for supporting an iron, an iron rockably supported with respect to the arm and having an air passage therethrough, a heating unit carried by the arm formed of cylindrical sections including an outer intake section, an intermediate warming passage and an inner tubular passage, an electric heating unit within the last mentioned member through which the air passes to be heated, and a pair of hingedly connected ironing plates pivotally mounted in the iron in the path of travel of the air therethrough.

9. In an iron for hat flanging machines, the combination of an arm for supporting an iron, an iron carried by said arm, a heating unit carried by the arm and having an air passage connected with the iron, an air supply connected with the heating unit for supplying air thereto and through the iron, said iron including an inner member having an air passage therethrough, ironing plates mounted in the outlet of the air passage, a filling of insulation surrounding the said inner shell and an outer covering enclosing the said insulating means.

10. In an iron for hat flanging machines, the combination of an arm for supporting an iron, an iron rockably supported with respect to the arm and having an air passage therethrough, means for limiting said rocking movement, a heating unit carried by the arm and having an air passage connected with that of the iron, means for supplying a flow of air to the heating unit and through the iron, a pair of hingedly connected ironing plates mounted in the mouth of the air passage through the iron to permit the same to better conform to the surface of a hat on which the iron is operating.

11. In an iron for hat flanging machines, a supporting arm and an electric heating unit carried thereby, an iron rockably supported on said arm, means for providing a current of air through the heating unit to the iron, a temperature control means within the iron to regulate the temperature of the air supplied to the iron.

12. In an iron for hat flanging machines, a supporting arm, an electric heating unit carried thereby, an iron rockably supported on said arm and having an air passage therethrough, means for providing a current of air to and through the heating unit and iron, pivotally mounted ironing plates positioned in the mouth of the air passage to be heated by the warm air flowing therethrough, a temperature control means within the arm to regulate the temperature of the air to the iron.

13. In an iron for hat flanging machines the combination with a supporting arm, of an iron carried by the support and having an air passage extending therethrough, ironing plates pivotally mounted in the mouth of said air intake and rockably connected to each other better to conform to the hat brim, one of the said plates being

larger than the other, an electric heating unit carried by the ironing arm and having a warm air duct connecting the iron, the intake end of the air duct of the iron being larger than the warm air pipe from the heater. 5

PAUL SCHULTZE.
